DESIGN FOR A SPORT BOOT

Paul D. Earl, New York, N. Y.

Application October 6, 1941, Serial No. 103,650

Term of patent 3½ years

To all whom it may concern:

Be it known that I, Paul D. Earl, a citizen of the United States of America, residing in New York city, county of New York and State of New York, have invented a new, original, and ornamental Design for a Sport Boot, of which the following is a specification, reference being had to the accompanying drawing, forming part thereof.

The figure on the drawing is a perspective view of a sport boot showing my new design, the opposite side presenting substantially the same appearance as the side shown.

I claim:

The ornamental design for a sport boot, substantially as shown and described.

PAUL D. EARL.
